UNITED STATES PATENT OFFICE.

FREDERICK PRICE, OF STECHFORD, BIRMINGHAM, ENGLAND, ASSIGNOR OF ONE-HALF
TO CHARLES BIRCH, OF WALSALL, ENGLAND.

TURRET TOOL-HOLDER FOR LATHES.

1,265,815.

Specification of Letters Patent.

Patented May 14, 1918.

Application filed October 10, 1917. Serial No. 195,782.

To all whom it may concern:

Be it known that I, FREDERICK PRICE, subject of the King of Great Britain, residing at Stechford, Birmingham, England, have 5 invented new and useful Improvements in and Relating to Turret Tool-Holders for Lathes, of which the following is a specification.

The invention relates to turret mountings 10 of the type in which the turret is permitted to move forwardly under the influence of a spring to clear a positioning device to permit the turret to be rotated to bring different tools into operation, the forward 15 movement being limited by a control rod and regulating nut. In this invention a turret mounting is employed in which a horizontal holder or socket part receives a hollow spigot portion of the turret, and a 20 spring between the holder and the turret urges the latter forward to clear a peg and hole or like positioning device between the two parts. The turret when thus projected forwardly may be rotated to bring the different 25 tools carried by it into operative position. The endwise movement of the turret is controlled by means of a sliding rod with a removable washer at one end and a handle nut or the like at the other. The handle nut 30 when unscrewed permits the spring to move the turret and when screwed up draws back the turret against the spring. By means of the removable washer the turret can be bodily removed in a very ready manner 35 when desired to change a turret or for any other purpose.

In order that the invention may be thoroughly understood and easily carried into practical effect a sheet of drawings illustrating the same is appended hereunto.

Figure 1 is an elevation of the turret and turret mounting.

Fig. 2 is a plan thereof.

Fig. 3 is a longitudinal sectional view.

Fig. 4 is an end view of the turret.

Fig. 5 shows the removable washer.

Figs. 6 and 7 are respectively end views and sections of a circular turret that may be employed.

The turret *a* is mounted in a holder *b* pivoted in any suitable manner on the cross slide *c*. As shown the holder pivots on a central stud or pillar and is held down and secured in any adjusted position by means 55 of the pins *d* which are secured in the slide

and pass through segmental slots *e* in the holder and receive binding nuts *f* as clearly shown at Figs. 1 and 2.

The holder has a horizontal socket part *g* at its forward end opening into a larger 60 chamber *j*, and a spigot part *k* (Fig. 3), preferably tubular on the turret *a*, enters the socket *g* of the holder, while a shouldered part *l* enters the larger chamber or recess *j*. Within the socket and spigot part a spring 65 *m* is arranged tending to press the turret outwardly and the turret may be held against the action of this spring for the purpose hereinafter stated by a pin or peg passing through the wall of the socket and 70 engaging a hole *n* of a series of holes or recesses in the spigot part *k*. In the larger chamber or recess *j* a hardened peg *o* may be driven or otherwise secured, adapted to engage one of a series of holes *p* in the face 75 of the shouldered part *l* of the turret *a* to position the same as any particular tool of those carried by the turret is required for operation. The number of holes in the said shouldered part will of course correspond 80 with the number of tool faces. As will be seen the turret rotates in a vertical plane for bringing the successive tools into operation.

The turret *a* and holder are bored axially, 85 see Fig. 3, and a rod *q* is arranged therein which is screwed at the tail end remote from the turret, and is operated by a handle nut *r*. The rotation of the rod *q* may be prevented by a feather key or by a set pin *s* through the holder engaging a groove *t* in 90 the rod. The forward end of the rod is necked down as at *u* and then provided with a head *v* and the latter may be engaged by a slotted washer *w*, see Fig. 5, passed over the neck and seating in a recess *x* in the end 95 of the turret.

A plain peg may be provided to engage the holes *n* of the spigot part *k* of the turret. Two pegs are preferably provided attached, for instance, by a chain or the like to the 100 machine one of a length to pass through the hole *y* in the holder *b* and engage the holes *n* of the spigot part *k* and the other, as shown at *z* being too short for this purpose, serves merely to plug the hole *y* and 105 prevent swarf, dirt, and the like from entering. The short peg *z* as shown at Fig. 3 is in place during normal working.

If it is desired to bring another tool into operation, the handle nut *r* is slackened and 110

the spring *m* urges the turret forward until the peg *o* is cleared when the turret can be turned by hand to the desired position (when the corresponding hole *p* will be opposite peg *o*) and again drawn in and secured by the operation of the handle nut *n*.

When it is desired to remove the turret the longer peg is substituted for the shorter one *s* so as to engage one of the holes *n* in 10 the spigot part *k* and prevent the turret moving forward under the action of the spring *m*. The handle nut *n* is then unscrewed and the rod *q* pushed forward until the head *v* and neck *u* project from the 15 turret when the anchoring washer *w* may be slipped off and then, if the retaining peg is withdrawn from the hole *n*, the turret may be bodily removed.

In the example illustrated in Figs. 1 to 4 20 in which a square turret is shown, it will be seen that tool holes or slots in the faces of the turret *a* instead of passing across in a plane at right angles to the plane of the axis or radial to the axis, are preferably set 25 at an incline so that the shank of one tool may overhang the turret, and yet coming behind the operative edge of the next tool being quite clear of same and any other tool set therein and the working position should 30 correspond to the top edge of the turret so that the working tool is uppermost and the operator's view of it is unobstructed.

The invention is not restricted to this particular arrangement of the tools in the turret 35 however, nor to the number of faces and tools provided on the turret.

As shown in Figs. 6 and 7 a circular turret may be used with the invention if desired, the tool recesses, six in this case, inclining outwardly as shown around the 40 turret axis. By pivoting the holder *b* on the slide by means of the nuts *f* and slots *e* the turret may readily be turned so that the tools set in this position may be directed in 45 the desired operative position with respect to the work.

The invention permits the rapid adjustment of the turret to change the particular tool for operation and also permits the 50 rapid changing of a turret for another of different form or with tools for further operations on the same work before its removal from the lathe.

What I claim then is:—

1. In a turret lathe, the combination with 55 a turret mounting comprising a holder, a turret rotatable in said holder, a positioning device to maintain the turret in position on the holder after rotation, a spring to move 60 the turret endwise to clear the positioning device, and means to limit the endwise movement of the turret, of a removable washer on said limiting means normally positioned in a recess in the turret, but capable, following an adjustment of the limiting means

relatively to the turret, of removal to permit removal of the turret from the holder.

2. In a turret lathe, the combination with 70 a turret mounting comprising a holder, a turret rotatable in said holder, a positioning device to maintain the turret in position on the holder after rotation, a spring to move the turret endwise to clear the positioning device, and a controlling rod and nut to limit the endwise movement of the turret, of 75 a removable washer on said rod, the latter having a head and neck to receive said washer which is normally positioned in a recess in the turret and thereby kept in position upon the rod but is capable of removal 80 from the latter upon the same being adjusted relatively to the turret to carry the washer out of the recess whereupon the turret may be removed from the holder.

3. In a turret lathe, in combination, a 85 holder, a turret rotatable and movable endwise therein, a positioning device on the holder, a spring arranged to move the turret relatively to the holder in one direction and clear of the positioning device, a controlling 90 rod and a nut thereon to move the turret in the opposite direction and into engagement with the positioning device said rod having a head and a neck, a washer adapted to removably fit upon the head and neck of the 95 rod and enter a recess in the turret to hold the latter in the holder, and means to temporarily lock the turret in the holder while the washer is being removed from the rod for the purpose described. 100

4. In a turret lathe, in combination, a holder, a slide upon which said holder is pivotally mounted, means to set the holder in an adjusted position about its pivot on the slide, a turret arranged telescopically within 105 the holder, a controlling rod passed through said holder and turret, and a removable washer on said rod to permit of the removal of the turret from the holder.

5. In a turret lathe, in combination, a 110 holder, a slide upon which said holder is pivotally mounted, means to set the holder in an adjusted position about its pivot on the slide, a turret, a spigot on said turret fitting rotatably and slidably within a socket 115 on the holder, a controlling rod passed through said holder and turret, and a removable washer on said rod to permit of the removal of the turret from the holder, said washer being normally prevented from displacement by engagement with a recess in the turret. 120

6. In a turret lathe, in combination, a holder, a turret rotatably and slidably arranged therein, a controlling rod passing 125 through said holder and turret, a washer removably mounted upon said rod to keep said turret in place and also permit of its removal from the holder, and means to adjust the rod, said turret having tool receiving 130

holes which are arranged at an incline in the faces of the turret, substantially as described.

7. In a turret lathe, in combination, a holder having a socket therein, a turret, a spigot part on said turret rotatable and slidably fitting within the socket of the holder, a spring arranged between the turret and holder and acting to urge the turret from the holder, a rod passing through said turret and holder, a removable washer on said rod engaging the turret, an adjusting nut handle on the rod engaging the holder, said rod, washer and nut handle serving to

draw the turret into the holder, a positioning pin in the holder engaged by one of a series of holes in the turret when the latter is drawn into the holder, and a peg in the holder adapted to enter one of a series of holes in the spigot part of the turret, substantially as and for the purpose described.

In testimony whereof I have signed my name to this specification in the presence of two subscribing witnesses.

FREDERICK PRICE.
